Inventors

Adolph Bangert & Friedrich May,
By their Attorney
R. K. Miller.

UNITED STATES PATENT OFFICE.

ADOLPH BANGERT AND FREDERICK MAY, OF NEW YORK, N. Y.; SAID FREDERICK MAY
ASSIGNOR OF HIS ENTIRE RIGHT TO CHARLES MAY, OF JERSEY CITY, NEW
JERSEY.

WRENCH.

Application filed July 18, 1921. Serial No. 485,611.

To all whom it may concern:

Be it known that we, ADOLPH BANGERT and FREDERICK MAY, citizens of the United States, residing at New York city, county 5 of New York, and State of New York, have invented certain new and useful Improvements in Wrenches, fully described and represented in the accompanying specification and drawing, forming a part of the same.

10 This invention relates to an improvement in combination tools.

The present invention has for its object the provision of a tool unit which, while combining the useful elements of various 15 tools constantly required in automobile work, shall be simple in construction and operation, and therefore economical in manufacture, durable, and highly efficient. The invention aims, also, to provide a novel wrench 20 construction as a part of such tool unit which shall be capable of easy and quick adjustments to the largest and smallest parts in automobile work, and the construction of which wholly obviates the objectionable feature of give or yield in wrenches of ordinary construction.

With these and other objects in view, the invention in a preferred embodiment will now be described in detail in connection with 30 the accompanying drawings, and the novel features thereof then be pointed out in the appended claim.

In the drawings—

Figure 1 is a side view of the complete 35 tool unit;

Fig. 2 is an edge view of the same; and

Figs. 3 and 4 are side views of the tool members before assembly.

Referring now to the drawings, and particularly to Fig. 1, the tool unit, combining the various tool elements hereinafter referred to, consists of two crossed members A, B pivoted at 10, so formed as to provide at one end of the tool jaws 1, 2 forming in effect a pair of pliers, and at the other end jaws 3, 4 of a wrench. One of the members, as A, for instance, is formed with an arcuate or thickened portion 5 having notches 6 formed on its outer or edge portion, the latter being adapted to engage a bail or

hook 7 pivoted in any convenient or suitable manner on the member B. The bail or hook 7 is preferably provided with a notched inner edge for holding engagement with the notches 6, and such notched surface is curved 55 as shown and so situated with respect to the pivotal point of the bail or hook that the raised or thickened portion 5 and its curved surface will permit the wrench jaws to open or close as such bail is shifted from 60 one end to the other of such curved notched surface. In the extreme positions of adjustment of the bail, the jaws 3, 4 of the wrench will be opened to their widest point or closed, as the case may be. When it is desired to use only the pliers or the tool elements associated therewith, the bail or hook 7 is readily swung entirely off of the member A. To facilitate adjustment and use of the wrench and pliers, a spring 8 is preferably 65 mounted on either of the members A or B, between them, with its free end normally pressing against the other member and tending to separate the wrench jaws and the pliers.

At a convenient point on the end of each of the wrench jaws 3 and 4, there is preferably provided a screw-driver tip *a*; while on the inner sides of such members are provided suitably formed cut-away portions *b* 80 for engagement with an automobile radiator cap. The plier jaws also are formed with pipe-engaging cut-away portions *c* and wire cutters *d*.

While we have described the invention as 85 particularly useful in automobile work, it will be understood that it may be used in all classes of machine work where such a tool unit is desirable. It is also to be understood that various modifications in constructions may be resorted to and still be within 90 the scope of the claim.

What is claimed is:

The combination, in a combination wrench, of two crossed and pivoted members, pipe- 95 wrench jaws formed at one end of said members, nut-wrench jaws formed at the opposite end of said members, the pivotal point of said members being near said pipe-wrench jaws, an arcuate surface formed on the outer 100

edge of one of said members near the nut-wrench jaws, and provided with notches on said surface, a bail pivotally secured to the other of said members at a point eccentric to said arcuate surface and extending there-over and having a plurality of notches formed on said bail and arranged to engage

the notches on said arcuate surface, and a spring normally tending to separate said pipe and nut wrench jaws. 10

In witness whereof, we have hereunto signed our names.

ADOLPH BANGERT.
FREDERICK MAY.
